CLAIM

We claim the ornamental design for a band for smart phone case, as shown and described.

DESCRIPTION

FIG. 1 is a perspective view of a band for smart phone case, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of a portion of FIG. 4;

FIG. 9 is an enlarged view of a portion of FIG. 5;

FIG. 10 is an enlarged view of a portion of FIG. 4;

FIG. 11 is an enlarged view of a portion of FIG. 5;

FIG. 12 is an enlarged view of FIGS. 6; and,

FIG. 13 is an enlarged view of FIG. 7.

The broken lines in the drawings of the band for smart phone case are for the purpose of indicating the enlarged portions of the article that form no part of the claimed design.

1 Claim, 13 Drawing Sheets
